CLAIM

The ornamental design for an electronic device display with graphical user interface applied to it, as shown and described.

DESCRIPTION

The patent file contains at least one drawing executed in color. Copies of this patent with a color drawing will be provided by the Office upon request and payment of the necessary fee.

FIG. 1 is a front view of an electronic device display with graphical user interface applied to it showing our new design; and,

FIG. 2 is a front view of a second embodiment thereof. The broken line showing of a display screen in the figures forms no part of the claimed design.
